Primary Examiner — T. Chase Nelson*Assistant Examiner* — Kathleen M Sims(74) *Attorney, Agent, or Firm* — Morgan, Lewis & Bockius LLP(57) **CLAIM**

The ornamental design for a drawer-shaped washing machine, as shown and described.

DESCRIPTION

FIG. 1 is a perspective view of a drawer-shaped washing machine showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a left side view thereof showing the state that the doors of the drawer-shaped washing machine have been closed.

The broken lines depict portions of the drawer-shaped washing machine that form no part of the claimed design.
